United States Patent Office.

H. GALMANN AND CHARLES RUHE, OF BUCHANAN, PENNSYLVANIA.

Letters Patent No. 99,305, dated February 1, 1870.

IMPROVED JOIST-PROTECTOR.

The Schedule referred to in these Letters Patent and making part of the same.

To all whom it may concern:

Be it known that we, H. GALMANN and CHARLES RUHE, of Buchanan, in the county of Allegheny, and State of Pennsylvania, have invented a new and improved Joist-Protector; and we do hereby declare that the following is a full, clear, and exact description thereof, which will enable others skilled in the art to make and use the same, reference being had to the accompanying drawing, forming part of this specification.

This invention relates to a new and useful improvement in a device for supporting and protecting joists in buildings, and consists in a cast-iron box-support, placed in the wall which the end of the joist enters, and by which it is protected, as will be hereinafter more fully described.

In the accompanying sheet of drawings—

Figure 1 represents the box-support in perspective.

Figure 2, in dotted lines, represents the end of a joist as when prepared for the box.

Similar letters of reference indicate corresponding parts.

A is the box-support or protector, which is made of cast-iron, and open only on one side, for receiving the end of the joist, as seen in the drawing. The interior of the protector is designed to be of the size, in height and width, of the joist.

From the lower end of the box, flanges B B extend so as to give it a good base to stand upon.

C C are horizontal partitions in the box, of which there may be more or less, and

D D represent slots made in the end of the joist, to correspond with the partition, so that when the end of the joist is inserted, it shall have more than one bearing to rest upon.

In many situations where joists are placed in walls, especially for lower floors, the wood is exposed to much dampness, and early decay consequently ensues. By the use of our box-protector, this difficulty is not experienced. The ends of the joists are protected from the effects of moisture, and maintained in a proper position in the wall.

Having thus described our invention,

We claim as new, and desire to secure by Letters Patent—

The joist-protector above described, with or without partitions C C.

H. GALMANN.
CHARLES RUHE.
